(57) **CLAIM**

The ornamental design for a golf cart enclosure, as shown and described.

DESCRIPTION

FIG. 1 is a front view of the golf cart enclosure showing my new design.

FIG. 2 is a back view thereof.

FIG. 3 is a side view thereof.

FIG. 4 is another side view thereof.

FIG. 5 is top view thereof.

FIG. 6 is bottom view thereof; and,

FIG. 7 is a perspective view of the golf cart enclosure in an environment of use.

The broken lines shown around the claimed design in the drawing view of FIG. 7 represent an environment of use and the broken lines shown in all of the figures form no part of the claimed design.

The graphical cross hatch pattern is a symbolic representation of a cloth fabric material that exists uniformly across all surfaces on which it is shown.
